COMBINED HUNTING SIGHT AND RANGE FINDER FOR BOW

Archie A. Jacobs, 1033 Avondale Road,
Paducah, Ky. 42001

Filed Sept. 25, 1975, Ser. No. 616,841

Term of patent 14 years

FIG. 1

U.S. CL. D22—5

Int. Cl. D22—05

FIG. 6

FIG. 2

FIG. 4

FIG. 5

FIG. 3

FIG. 1 is a front view of a combined hunting sight and range finder for bow showing my new design;

FIG. 2 is a side view of the sight and range finder shown in FIG. 1 and in accordance with my design;

FIG. 3 is a side view looking in from the side opposite that shown in FIG. 2 of the sight and range finder of FIG. 1 and in accordance with my design;

FIG. 4 is a rear view of the sight and range finder as illustrated in FIG. 1 and in accordance with my design;

FIG. 5 is a bottom view of the sight and range finder as shown in FIG. 1 and in accordance with my design; and

FIG. 6 is a perspective view of the sight and range finder of FIG. 1 and in accordance with my design.

The drawing has been lined for fluorescent yellow covering alternate sighting pins and the face of the range finder.

I claim:

The ornamental design for a combined hunting sight and range finder for bow, as shown and described.
